In Czechoslovakia December 11, 1947

3 Claims. (Cl. 192—25)

1

The present invention relates to a starting mechanism for stamping machines used for cutting leather, paper, textile materials and the like, in which the working stroke of the stamping arm or post is controlled by means of an eccentric.

The purpose of a starting mechanism of this type is first to put in operation the coupling which connects the driving wheel, or the driving shaft, with the eccentric just referred to and thereby to impart rotation to the latter, and then to provide a safety characteristic for the coupling in such a way that the eccentric, and with the same the stamping arm, does not perform more than a single stroke even if the starting member is still in its working position. In this way accidents are avoided which may take place in cases when an unreliable starting device is used and the assistant omits to release in time the starting lever so that the stamping arm will perform a further and unexpected stroke.

A number of mechanically or electro-magnetically operated starting devices of this type are known. However, the prior devices are all complicated and due to their complexity are not reliable in operation. In the electro-magnetically operated devices disturbances and damage in the windings or burning of the contacts often take place. Moreover, due to their complexity, the devices of this type are very expensive.

The present invention permits to comply with all the above quoted requirements by the use of a very simple constructional arrangement.

The main feature of the invention resides therein that in a starting mechanism for power driven stamping machines provided with a coupling of the so called one revolution type, the control lever system between a starting member operated by the assistant and the operating element of the coupling includes a triple-armed lever, one arm of which co-operates with a catch or pawl, while the other two arms are positively controlled in both directions of the rocking movement of the lever. When the triple-armed lever is released by depression of the starting member controlled by the assistant, the lever is placed under the influence of an eccentric which operates, independently of the position of the starting lever and against the pressure of a spring, to place a finger in the path of the operating element of the coupling and to positively disengage the coupling. Thereby a repetition of the working stroke is prevented even if for any reason the assistant omits to release the starting lever.

Further advantages and features of the present

2

invention will appear from following description of an embodiment of the same when read in conjunction with the accompanying drawing, in which:

5 Figure 1 shows the construction of the clutch of a driving device;

Figure 2 shows the mechanism for controlling the clutch of the driving device;

Figure 3 shows the starting mechanism in its 10 initial position;

Figure 4 shows the same mechanism in its working position; and

Figure 5 shows the arrangement of the starting 15 lever.

Referring to the drawing, the driving device for the stamping arm (not shown) of a stamping machine is constructed in the usual manner and comprises a pulley 4 which is driven by an electric motor (not shown) and is mounted for free rotation on a shaft 3 by means of roller or like bearings 2, Fig. 1. The pulley is provided with a crown or drum 4 having a friction clutch 5 arranged within the hollow space of the same. The friction clutch 5 can be expanded in the manner

20 of a brake disc by means of a screw key 6 which is operated by a hollow pin 7 slidably mounted in the body of an eccentric 8 fastened on the shaft 3. The shaft 3, which carries the eccentric (not shown) for operating the stamping arm, is mounted in the body of the machine frame 9 which has fastened thereon a ring 10 provided with a cam track 11. In the bore of the pin 7 is lodged a spring 12 which bears against the ring 10 and urges the pin 7 to the left as viewed in Fig. 1. The pin 7 is urged in the same direction

25 by the cam track 11 of the ring 10 when the shaft 3 is rotated. Displacement of the pin 7 to the left, when the shaft 3 is in rest, is prevented by a bevelled finger 13 of a triple-armed lever 14 which is mounted for rocking movement about a pivot 15. One arm of the triple-armed lever 14 is provided with an eye 16 while a second arm of the lever carries a follower 17 co-operating 30 with the eccentric 8.

35 Through the opening of the eye 16 passes a catch or pawl 18 which is mounted rotatably about a pin 19 fastened in the body of a bracket 20 carried by the machine frame. The catch or pawl 18 is surrounded by a spring 21 bearing with its top end against a projection 22 of the bracket 20 and pressing with its bottom end against the eye 16 of the triple-armed lever 14. The free end of the pawl 18 is provided with a nose 23 which has a forked portion 24 and a recess 25

40 on its under side, Figures 2, 3 and 4. The bottom 45

50

part of the eye 16 has screwed thereon a washer 26 with which the nose 23 is in contact. The lower part of the pawl 18 is provided also with a socket 27 in which a spring 28 is lodged, the other end of the spring being threaded on a stud 29 fastened on the bracket 20. The spring 28 urges constantly the locking pawl 18 to the right, as viewed in Figure 3, that is to say in counter-clockwise direction.

The bracket 20 carries also a pin 30 which passes through a longitudinal slot 31 provided in a lever 32, whose one end projects through an opening 33 out of the bracket 20 and has a nose 34, while the other end of the lever 32 has connected thereto a spring 35 which constantly tends to pull the lever to the right. That end of the lever 32 which is provided with the nose 34 passes through the forked portion 24 of the pawl 18, the arrangement being such that in the initial position the nose 34 engages in the recess 25 of the nose 23.

On the pivot pin 36 of the lever 32 is mounted a draw bar 37 which is controlled by a starting lever 38, Fig. 5, actuated by the assistant's knee, the control being effected through the intermediary of a double-armed lever 39 rotatably mounted about a pivot pin 40 on the machine frame.

The described mechanism operates as follows:

In the initial position, when the machine is not in operation, the clutch of the driving device occupies the position shown in Fig. 1 and the starting mechanism occupies the position shown in Fig. 2. In this position the pulley 1 rotates freely and does not drive the shaft 3 because the friction clutch 5 is not expanded, since the hollow pin 7 for actuating the key 6 is in its right hand extreme position, in which it is retained by the bevelled finger 13 of the triple-armed lever 14, the finger occupying the position shown in full lines in Figure 2. In this initial position, the eye 16 of the triple-armed lever 14 is held over the washer 26 against the nose 23 of the locking pawl 18, the spring 21 being compressed. Thus the locking pawl 18, and the lever 32 as well, occupy their right hand extreme positions as shown in Fig. 3.

If a working stroke is to be effected, the assistant exerts pressure with his knee on the starting lever 38 in the direction of the arrow shown in Figure 5, whereby the lever 32 is pulled to the left on the pin 30 through the intermediary of the double-armed lever 39 and the draw rod 37. As result of this movement, the lever 32 which by means of its nose 34 engages in the recess 25 of the locking pawl 18, causes the latter to turn about the pivot 19 in clockwise direction, whereby the nose 23 is disengaged from beneath the washer 26 of the eye 16, so that the compressed spring 21 can depress the eye 16 and cause the triple-armed lever 14 to turn in a counter-clockwise direction (as viewed in Fig. 2) to the position shown in dotted lines. In this position of the lever 14, the bevelled finger 13 of the same is out of contact with the hollow pin 7 which then is shifted to the left, as viewed in Fig. 1, under the effect of the spring 12 and causes the screw key 6 to turn in clockwise direction whereby the friction clutch 5 is expanded and pressed against the drum 4. In this way connection is established between the pulley 1 and the driving shaft 3 and a working stroke takes place.

For effecting a working stroke, a single revolution of the shaft 3 is required and upon com-

pletion of the revolution it is always necessary to interrupt the connection of the shaft with the pulley 1, so as to avoid a repetition of the working stroke and a possible injury of the assistant. No further working stroke should take place even if the assistant keeps the starting lever 38 in depressed position. For the sake of his safety, the assistant must first release the starting lever and then depress it again if another working stroke is required.

Assuming that the assistant has released the starting lever 38, the disengagement of the clutch is effected as follows: The eccentric 8 whose initial position is shown in solid lines in Fig. 2, is rotated by the shaft 3 in counterclockwise direction until it reaches the position shown in dotted lines in which the eccentric acts upon the roller 17 in such a way as to rock the triple-armed lever 14 in clockwise direction from the position shown in dotted lines in Fig. 2 to its initial position, the spring 21 being compressed again at the same time. At this moment the locking pawl 18 rocks under the effect of the compressed spring 28 to the right from the position shown in Figure 4 to its initial position shown in Fig. 3, in which the pawl 18 engages beneath the washer 26 on the eye 16 of the triple-armed lever 14 and holds rigidly the latter in this position during the remaining part of the revolution of the shaft 3, that is also during the period when the eccentric 8 does not co-operate any longer with the roller 17. If the starting lever 38 has been released, the movement of the locking pawl 18 to the right is accompanied by movement of the lever 32 under the action of the spring 35 so that the starting device will reassume its neutral position shown in Figure 3. When the shaft 3 with the eccentric 8 arrive to the position shown in solid lines in Figure 2, the bevelled finger 13 of the triple-armed lever 14 is positioned in the path of the hollow pin 7, the bevelled face of the finger 13 causing the hollow pin 7 to be shifted to the right so that the screw key 6 is rotated to the right. As a consequence the friction clutch 5 is contracted, the connection with the drum 4 of the pulley is removed and the shaft 3 is arrested by a conventional brake (not shown).

Assuming that for any reason the assistant omits to release the starting lever 38, the shaft 3 must be arrested nevertheless so as to avoid a repetition of the working stroke of the stamping arm. In such a case the lever 32 remains in its position shown in Fig. 4 while all the other parts perform the aforementioned operations. The movement of the pawl 18 to the right without simultaneous movement of the lever 32 is made possible by the forked portion 24 which passes freely over the nose 34 of the lever 32. The nose 23 of the pawl 18 engages again beneath the washer 26 of the eye 16 and the bevelled finger 13 of the triple-armed lever 14 by its action upon the hollow pin 7 interrupts in the described manner the connection between the pulley 1 and the shaft 3.

If in the case just referred to the assistant wishes to provoke another working stroke, he must first release the starting lever 38 whereby the lever 32 under the influence of the tension of the spring 35 will return to its initial position shown in Figure 3, in which the nose 34 engages in the recess 25 of the pawl 18. During this back movement the lever 32 performs also a small rotation about the pivot 30 in a counter-clockwise direction, which rotation is permitted by the spring 35 being anchored beneath the pivot 30

and tending constantly to rotate the lever 32 in this direction. By a further depression of the starting lever it is now possible to effect another working stroke in the aforescribed manner.

What I claim is:

1. In a starting mechanism for power driven stamping machines provided with a one revolution clutch, the provision in the control lever system between a starting member operated by the assistant and the clutch operating member, of a triple-armed lever having one of its arms provided with an eye at the outer end thereof, a retaining pawl having a nose adapted to engage with said eye of the lever, cam means co-operating with the other two arms of said lever positively in opposite directions during one revolution of the clutch, a spring urged operating pin for the clutch, a bevelled finger on the triple-armed lever for operating the pin, the said first mentioned arm of the triple-armed lever being arranged to be retained by, or released from, the said pawl against the action of a spring adapted to interrupt the connection of the said finger with the clutch operating pin, a slideable and partially rotatable lever co-operating with the said pawl and operated by a starting lever, and a fork formed at the free end of the said pawl and through which a nose on the said slideable and partially rotatable lever is adapted to pass.

2. In a starting mechanism for power driven stamping machines provided with a one revolution clutch, the provision in the control lever system between a starting member operated by the assistant and the clutch operating member, of a triple-armed lever having one of its arms provided with an eye at the outer end thereof, a retaining pawl having a nose adapted to engage with said eye of the lever, cam means co-operating with the other two arms of said lever positively in opposite directions during one revolution of the clutch, a spring urged operating pin for the clutch, a bevelled finger on the triple-armed lever for operating the pin, the said first mentioned arm of the triple-armed lever being arranged to be retained by, or released from, the said pawl against the action of a spring adapted to interrupt the connection of the said finger with the clutch operating pin, a slideable and partially rotatable lever co-operating with the said pawl and operated by a starting lever, a fork formed at the free end of the said pawl and through which a nose on the said slideable and partially rotatable lever is adapted to pass, a draw rod connected to a starting lever and

controlling the movement of the said slideable and partially rotatable lever in one direction, and a spring anchored at a point beneath the last mentioned lever and controlling the movement of the latter in the opposite direction.

3. In a starting mechanism for power driven stamping machines provided with a one revolution clutch, the provision in the control lever system between a starting member operated by the assistant and the clutch operating member, of a triple-armed lever having one of its arms provided with an eye at the outer end thereof, a retaining pawl having a nose adapted to engage with said eye of the lever, cam means co-operating with the other two arms of said lever positively in opposite directions during one revolution of the clutch, a spring urged operating pin for the clutch, a bevelled finger on the triple-armed lever for operating the pin, the said first mentioned arm of the triple-armed lever being arranged to be retained by, or released from, the said pawl against the action of a spring adapted to interrupt the connection of the said finger with the clutch operating pin, a slideable and partially rotatable lever co-operating with the said pawl and operated by a starting lever, a fork formed on the free end of the said pawl and through which a nose on the said slideable and partially rotatable lever is adapted to pass, a draw rod connected to a starting lever and controlling the movement of the said slideable and partially rotatable lever in one direction, and a spring anchored at a point beneath the last mentioned lever and controlling the movement of the latter in the opposite direction, said cam being adapted, upon release of the said triple-armed lever from the nose of said pawl, to rock the said triple-armed lever against spring pressure so as to place the said bevelled finger in the path of the said clutch operating pin and to disengage the clutch independently of the position of the starting lever.
